CLAIM

The ornamental design for a bionic finger blade set, as shown and described.

DESCRIPTION

FIG. 1 is a perspective view of a base of a bionic finger blade set, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof;

FIG. 9 is a perspective view of four blade heads of the bionic finger blade set, the base of the bionic finger blade set is removed for ease of illustration;

FIG. 10 is another perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a perspective view of the bionic finger blade set where the first blade head is connected with the base;

FIG. 16 is a perspective view of the bionic finger blade set where the second blade head is connected with the base;

FIG. 17 is a perspective view of the bionic finger blade set where the third blade head is connected with the base;

FIG. 18 is a perspective view of the bionic finger blade set where the fourth blade head is connected with the base;

FIG. 19 is an enlarged view of portion 19 shown in FIG. 9; and,

FIG. 20 is an enlarged view of portion 20 shown in FIG. 13. In the drawing, the dashed broken lines depict portions of the bionic finger blade set that form no part of the claimed design. The dot-dash lines represent boundaries of the enlarged figures and form no part of the claimed design.
